Primary Examiner — Eric Goodman*Assistant Examiner* — Amy Wierenga(74) *Attorney, Agent, or Firm* — Hudak, Shunk & Farine Co. LPA(57) **CLAIM**

The ornamental design for a female hose fitting, as shown and described.

DESCRIPTION

FIG. 1 is a side view of a female hose fitting, wherein the opposite side is a mirror image thereof;

FIG. 2 is a rear side perspective view thereof;

FIG. 3 is a front side perspective view thereof;

FIG. 4 is a front view thereof; and,

FIG. 5 is a rear view thereof.

The broken lines in the drawings depict portions of the female hose fitting that form no part of the claim.
